(57) **CLAIM**

The ornamental design for a battery charger for earphones, as shown and described.

DESCRIPTION

FIG. 1 is a right, front, and top perspective view of a battery charger for earphones, shown closed in a first configuration; FIG. 2 is a left, rear, and top perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a left side elevational view thereof; FIG. 8 is a right side elevational view thereof; FIG. 9 is a right, front, and top perspective view of the battery charger for earphones of FIG. 1, shown open in a second configuration; FIG. 10 is a front elevational view thereof; FIG. 11 is a rear elevational view thereof; FIG. 12 is a top plan view thereof; FIG. 13 is a bottom plan view thereof; FIG. 14 is a left side elevational view thereof; FIG. 15 is a right side elevational view thereof; FIG. 16 is a cross-sectional right side elevational view of the battery charger for earphones of FIG. 1, taken in the direction of 16-16 of FIG. 3; FIG. 17 is a cross-sectional right side elevational view thereof, taken in the direction of 17-17 of FIG. 3; FIG. 18 is a cross-sectional front elevational view thereof, taken in the direction of 18-18 of FIG. 5; and, FIG. 19 is a cross-sectional front elevational view thereof, taken in the direction of 19-19 of FIG. 5. The broken lines in the drawings depict portions of the battery charger for earphones that form no part of the claimed design.
